UNITED STATES PATENT OFFICE.

JOHN D. LYNDE, OF PHILADELPHIA, PENNSYLVANIA.

IMPROVED SODA-WATER APPARATUS.

Specification forming part of Letters Patent No. 40,347, dated October 20, 1863.

To all whom it may concern:

Be it known that I, JOHN D. LYNDE, of Philadelphia, in the county of Philadelphia and State of Pennsylvania, have invented a new and useful Improvement in Soda-Water Apparatus; and I do hereby declare that the following is a full, clear, and exact description of the construction and operation of the same, reference being had to the annexed drawings, making a part of this specification, in which—

Figure 1 is a perspective view; Figs. 2, 3, and 4, transverse sections of parts; Fig. 5, a top view of a part with a portion removed, and Fig. 6 a view of a part inverted. Fig. 7 is also a perspective view of a part.

In Fig. 1, A is a fountain in common use; B, the measuring-chamber; C, the filling-cock, and D the small fountain, of any required size, to be filled to a given extent with aerated water from A.

Fig. 2 shows the construction of the small fountain D. a, the lining, is of glass, earthenware, or metal, or any suitable material, provided with a valve-faucet stopper, constructed as follows, of metal and rubber: b is a mouth-piece screwed into the mouth or fixed tightly to the top of the fountain, making a tight joint by means of the packing c. Through b, in an easy hole, works the hollow valve-stem d, in which the hole from the top connects with the cross-opening near its lower end. Just below and tapping this cross-opening is an annular depression sufficient to hold the rubber valving, Fig. 7.

e is a rubber spring, surrounding the valve-stem, serving to hold the valve closed and also as a packing when the fountain is being filled. When the parts of the stopper are in place, the opening in the bottom of b will be securely closed, the valve-ring, Fig. 7, becoming a packing between the lower edge caused by the annular depression and the inner edge of lower end of b. The tube a', extending nearly to the bottom of the fountain, is connected to b by the thimble a'', which is screwed onto the lower end of b and incloses the valve in the chamber thus formed.

g is a metal case, a little larger than the lining a. The interstice h is filled with plaster-of-paris or any substance which may be poured in and packed or hardened without shrinking from either vessel or be affected by temperature, so that the strength of both a and g may

be combined to resist the pressure caused by the contents of a.

Figs. 3, 5, and 6 will explain the filling-cock C.

Fig. 3 shows the channel h', through which the water and gas are passed. i is the air-channel stopped by the screw-valve n; j, the rubber packing in the mouth-piece, to fit over the valve-stem d; k, the channeled gate, held firmly on its packed seat l by the screw m.

Fig. 5 is C with the gate K removed, which is shown inverted, Fig. 6. It will be seen that water passing in through p would come up in hole 1. Now, if the gate K is so placed as to bring hole 5 over 1, the water will pass through the channel in K and out through holes 4 and 3. Then, by turning K so that 4 will be over 2, a like connection will be made with q, while the former connection with p will be closed.

Fig. 4 is a transverse section of the measuring-chamber B, which is constructed of any desirable material and supplied with three pipes, r s t, two of which connect only with the top, while the other reaches nearly to the bottom. Water enters through r and passes out through t. Gas passes out and in through s. r is connected with the bottom of A, s with the top of A, and t with the filler C.

The operation is as follows: A is filled two-thirds full of water, which is then charged with carbonic-acid gas, let in through the pipe u, of the requisite pressure for working. The cock v in pipe r is then opened and water passes from A and fills B. v is then closed. The fountain D to be filled is laid on the rack Z, which is at such an inclination that when D is three-fourths full the open end of pipe a' will be above water. The filling-cock C is fastened firmly to the lower end of the inclined rack. D is then slipped down the rack until the valve-stem d enters the hole h', when it is firmly held with sufficient force to close the joint tightly. This pressure will then open the valve in the stopper. The gate K is then set so as to connect holes 1 and 5 with 4 and 3, when the water in B will be forced by the gas in A (coming through s) through t and into the fountain D. Closing the connection made by the gate, the air is let out of D by opening the valve n, after which gas is let into D by same pipe which brought the water. As it is desirable that B should always be filled at a uniform pressure, q is supplied

with a pipe connecting with a fountain filled with gas at such a pressure as required, so that after the above-described operation the gate K may be turned to make a connection with *q*, when gas will flow into or out of D, as may be necessary from greater or less pressure in A, thus securing a uniform pressure in D. The cap is then placed over the stopper to protect it during transportation.

What I claim as my invention, and desire to secure by Letters Patent, is—

1. The measuring-chamber B, the fountain D, and the improved valve *f*, all constructed and operated substantially as described.

2. The construction and arrangement of the cock C, as described, by means of which I am enabled to introduce through hole *h'* water or gas at a given pressure, at will.

3. The combination of the fountain D with the valve-stopper and its use in connection with the apparatus constructed, substantially as described, for the purpose of being filled and charged with aerated water or any liquids to be held and discharged under pressure.

JOHN D. LYNDE.
